DRILLING MACHINE

John E. Elf, Cecil E. Lucas, and Theodore Christie,
Rochester, N. Y.Continuation of application Serial No. 276,264,
May 29, 1939. This application March 20, 1940,
Serial No. 325,012

9 Claims. (Cl. 164—86)

This invention relates to drilling machines for paper, felt, leather, cloth or other similar sheet material or a combination of such material and the invention has for its principal object to provide a manually operable drilling mechanism for a drilling machine.

Another object of this invention is to provide the drilling machine with novel operating means for the drill thereof.

Both these and other objects and attendant advantages of the invention will become more readily apparent from the detailed description thereof which follows, reference being had to the accompanying drawings in which

Figure 1 is a side elevation and partial section of the drilling machine.

Figure 2 is a horizontal sectional view taken on the line 2—2 of Figure 1.

Figure 3 is a detail vertical section taken on the line 3—3 of Figure 1.

Figure 4 is a detail vertical section taken on the line 4—4 of Figure 1.

Figure 5 is a front elevation of the drilling mechanism.

Figure 6 is an enlarged vertical sectional view of the operating spindle of the machine.

Figure 7 is a detail sectional view of the drill and a portion of the spindle to which it is attached.

This application is a continuation of our prior application Serial No. 276,264 filed May 29, 1939. The drilling machine forming the subject matter of the present invention is especially adapted for use in offices, small book binderies, in fact for any place of business which requires the perforation of paper or other sheet material in quantities which do not warrant the use of a power driven machine. Hand operated punches are at present used for perforating small numbers of sheets at a time but this at best is a slow and therefore costly way of perforating sheet material. With the present manually operated machine many times the number of sheets which can be collectively punched by hand at a time may be collectively drilled by our hand operated drilling machine at one time.

As illustrated in the figures of the drawings, the drilling machine has a base 1 which carries in the middle and the rear thereof the upright 2. A pair of guide rods 3, 3 are spacedly supported in front of the upright and are mounted to slide in the horizontal brackets 4 and 5 which form part of the upright 2 and extend forward thereof. Mounted to move with the guide rods 3, 3 and adjusted to slide thereon is the spindle car-

rier 6 which has the spindle sleeve 7 adjustably held clamped therein. For this purpose the spindle carrier 6 is split at the rear and can be drawn together to rigidly clamp the spindle sleeve 7 in place in the spindle carrier. A hollow spindle 8 is journaled in the sleeve 7 for the operation of a drill and is operated by the mechanism that will hereinafter be described.

The lower end of the guide rods 3, 3 carry the pressure plate 9 and surrounding the guide rods between the pressure plate and the under side of the bracket 5 are the expansion springs 10, 10. These springs are adapted to force the pressure plate 9 against the stack of sheets to be drilled so as to hold the sheets compressed while the drilling operation takes place. To release the pressure of the plate 9 on the sheets after each drilling operation, the guide rods 3, 3 carry the collars 11, 11 which engage the top of the spindle carrier 6 for movement thereby in order to raise the guide rods and move the pressure plates away from the sheets on the upward movement of the spindle after the drilling operation has been completed. The spindle carrier in its normally elevated position illustrated in Figure 5 thus holds the pressure plate 9 in a correspondingly elevated position with the springs 10, 10 compressed between it and the bracket 5.

Movement is imparted to the spindle carrier by the bifurcated lever arm 12 which embraces the carrier and is pivotally attached thereto at 13, 13. The ends of the lever arm 12 are pivotally connected to the links 14, 14 which in turn are mounted to swing at 15, 15 on opposite sides of the upright 2 near the bottom thereof. In this way the pivotal connections between the lever arm 12, the upright 2 and the spindle carrier 6 permit the movement of the spindle carrier on the guide rods 3, 3 and the movement of the guide rods in the brackets 4 and 5 on the operation of the drilling machine by the lever arm. When the lever arm is raised into the dotted line position illustrated in Figure 1, the pivotal connection between it and the links 14, 14 has been moved past the center line between the pivotal connection 13 of the lever arm to the carrier and the pivotal mounting 15 of the links on the upright 2, and this holds the spindle carrier 6 and with it the pressure plate 9 in a normally inoperative elevated position with the springs 10, 10 held compressed.

For the drilling operation the lever arm is lowered so as to permit the expansion of the springs 10, 10 for the downward movement of the guide rods 3, 3 with the pressure plate 9 on the move-

ment of the spindle carrier by the lever arm. Movement of the pressure plate and the guide rods is arrested when the pressure plate rests on top of the stacks of sheets to be perforated and holds these sheets compressed while the spindle carrier with the spindle is moved further to have the drill 16 at the bottom of the spindle pass thru an opening in the pressure plate and drill the stack of the sheets in the manner that will hereinafter be described. After the sheets are drilled, the lever arm 12 is raised to first withdraw the drill from the perforation it has drilled into the sheets and then raise the pressure plate 9 to release its pressure from the sheets.

15 With the spindle in a raised position the stack of sheets is released so that it may be removed or relocated for the next hole to be drilled there-thru. To facilitate the movement of the sheets and provide for an accurate positioning thereof 20 relative to the drill, a tray 11 is mounted to slide on the base 1 in front of the upright 2. This tray is preferably made of sheet metal and is slidably mounted on the rails 19, 19 which are held fixed on the base and are made up of wood or other 25 suitable non-metallic material. A guide 20, fastened to the under side of the tray as illustrated in Figure 1, engages between two of the rails 19 so as to guide the tray in a straight line movement on the base. A gauge rod 22 is carried in 30 an elevated position by the tray so as to move therewith. Gauge members 23, 23 are movable on this gauge rod so that they can be adjustably held fixed thereon by means of their thumb screw 24. Each of the gauge members 23 has an 35 angular groove 25 in the top thereof to have the wedge shaped bottom of the locking latch 26 engage therewith. This locking latch is mounted in the bracket 5 and is vertically movable therein. For its operation the latch is provided with the 40 latch rod 27 which extends upwardly therefrom and passes thru the lug 28 of the spindle carrier 6. At the top, the latch rod carries the lock nuts 29, 29 which are adjustably threaded thereon for engagement by the top of the lug 28 to 45 provide for the raising of the latch rod on the last part of the upward motion of the spindle carrier. In this way the latch is disengaged from the gauge member on the withdrawal of the drill after each drilling operation. Mounted on 50 top of the bracket 5 so as to surround the latch 26 and latch rod 27 in its vertical movement, is a hollow cap 30 and in its is provided a spring 31 which operates to move the latch 26 into engagement with a gauge member 23 on the downward 55 movement of the spindle carrier which releases the latch rod from its elevated inoperative position.

55 The drilling mechanism which is operated by the movement of the lever arm 12 is illustrated in detail in Figures 6 and 7 and comprises a spindle made up of the non-rotating spindle sleeve 7 and the rotating hollow spindle 8. The latter is mounted to rotate and is movable end-wise in and out of the sleeve 7 and carries the hollow spiral 32. This spiral is threaded thru the nut 33 carried by the sleeve 7 so that when the spindle 8 is forced upward into the sleeve on the downward movement of the spindle carrier, the spiral 32 and with it the spindle 8 is rotated.

70 The bottom of the spindle 8 is closed by the cap 34 and holds the thrust ball bearing 36 in place in the bottom of the spindle for the support of the coil spring 37 which extends thru the hollow spindle 8, its spiral extension 32 and the spindle sleeve extension 38 against the ball bearing 40

located in the top of the sleeve extension 38. A cap 39 at the top of the sleeve extension 38 holds the thrust ball bearing 40 in place therein. In this way the coil spring 37 is held between two thrust bearings, one at the top and the other at the bottom of the spindle. As above described, the upward movement of the hollow spiral thru the nut 33 of the spindle sleeve causes the spindle to rotate in one direction. This upward movement of the spindle compresses the coil spring 10 37 so that its pressure and the rotation of the hollow spindle 8 cause the drill 16 to rotate while being forced thru the sheet material for the drilling operation. An upward movement of the lever arm 12 with the drill in drilling engagement in the sheet stock causes the nut 33 to rotate the spiral in the opposite direction so that while the spring 37 remains compressed within the spindle, the drilling operation of the drill continues with the drill rotating in the opposite 20 direction. In this way one or more movements of the lever arm 12 will cause the drill 16 to be rotatively forced into the sheet material until it is completely perforated thereby. This operation takes place whether the lever arm is given its 25 full range of movement or only a partial movement in either direction.

To supplement the action of the spring 37 in forcing the drill thru the sheet material on the rotation thereof, a spring 51 surrounds the outside of the spindle 8 and is interposed between the thrust ball bearing 52 and the washer 53 at the bottom of the spindle sleeve 7. In this way the spring 51 is jointly compressed with the spring 37 so that both springs exert their downward pressure on the spindle for the drilling operation during the rotation of the drill.

For the rotation of the drill 16 by the spindle, the cap 34 at the bottom thereof is provided with a threaded tubular extension 41 which carries the 40 keys or lugs 42 on the end thereof. The drill 16 has an enlarged head 43 which is slotted at the top to receive the lugs or keys 42 and the locking sleeve 44 which surrounds the drill head is threaded onto the extension 41 of the cap 34 to 45 hold the drill locked to the spindle.

The drill proper comprises a straight hollow shank with an enlarged cutting edge at the bottom thereof. The latter is formed by a short cylindrical outer wall and an inclined or beveled inner wall. The beveled inner wall gradually reduces the opening leading into the hollow drill up to the opening 45. Above this opening the inside diameter of the drill is enlarged and a short inclined shoulder 46 extends from the reduced 55 opening 45 to this enlarged inner cylindrical bore of the drill shank.

Due to the fact that the drilling mechanism is manually operated, it is imperative that the drill be forced thru the sheets with a minimum effort 60 on the part of the operator. This is accomplished by the drill because of its enlarged cutting edge which perforates the sheets with a hole larger in diameter than the diameter of the outside of the hollow shank of the drill and thus reduces to a minimum the friction between the rotating drill and the wall of the cut holes in the sheet stock. The discs or chips cut from the sheets are forced into the drill and are gradually 65 cupped by the inwardly tapering wall above the cutting edge until they have been forced past the opening 45 in the drill. This causes the chips to be set into an inverted cup shaped form, which 70 form they retain within the enlarged hollow drill 75

shank after the chips have been forced thru the opening 45.

Removably threaded into the top of the head 43 of the drill 16 is the discharge tube 54. This tube forms an extension of the drill so that the chips may loosely pass therethru and be discharged from an opening 55 in the side thereof into the chute 56 located at the top of the spindle and fastened to the collar 57 of the cap 39. In this way the chips are discharged from the drilling machine to one side thereof.

The discharge tube 54 is provided with a knurled end 58 which forms a handle with which the tube may be inserted thru the discharge 15 chute 56 and the spindle and threaded into the top of the drill 16. Various diameter discharge tubes are used to have them correspond with the size drill which is used in the drilling machine in order to efficiently carry off the chips 20 from the drill.

In the base 1 in line with the drill 16 are superimposed a series of freely rotating fiber washers 50, 50 so that when the drill is forced thru the sheet material its cutting edge may enter the 25 surface of the uppermost of these discs and have the discs rotate therewith to prevent injury to the cutting edge of the drill.

In order to further preserve the cutting edge of the drill, the drilling machine is provided with 30 an adjustable stop for the spindle so that the downward movement of the spindle may be arrested at a point just after the cutting edge of the drill has penetrated the bottom sheet of the material that is being perforated thereby. This 35 stop is located to one side of the cap 34 at the bottom of the spindle and comprises a freely rotating disc 60 which is mounted to rotate on the shank 61 on top of its flange 62. The shank 61 is mounted to vertically slide in the bracket 40 5 and a knurled nut 63 is threaded on the shank above the bracket 5. A keyway 64 is provided in the side of the shank so that the end of the set screw 65 can engage therewith and keep it from rotating while the nut 63 is being rotated 45 to cause the shank 61 to either move up or down in the bracket 5. In this way the freely rotating disc 60 may be raised or lowered to serve as a variable stop for the spindle of the drilling machine by having it engage the overhanging 50 shoulder of the cap 34 of the spindle and thus stop the downward movement of the spindle at a predetermined point while the disc 60 rotates with the spindle. After the stop has been set in its proper position the set screw 65 is tightened 55 so that the shank cannot be moved in either direction until it is released for a new adjustment.

In order to cushion any contact between the lug 28 of the spindle carrier and the top of the cap 30, a rubber pad 66 surrounds the latch rod 60 27 on top of the cap.

We claim:

1. In a drilling machine the combination of a longitudinally movable internally threaded spindle sleeve, a spindle movable in and out of one end of said spindle sleeve, a spiral on said hollow spindle in threaded engagement with said spindle sleeve, a spring within said spindle sleeve for compression between them on the movement of the spindle into the spindle sleeve, a drill at the bottom of said spindle, means for forcing said spindle into said spindle sleeve to compress said spring and cause the rotation of said spindle with said drill by said spiral in one direction and allow said spindle to be forced out of said spindle sleeve

by said spring to cause the rotation of said spindle with said drill in the reverse direction.

2. In a drilling machine the combination as set forth in claim 1 including a spring surrounding said spindle held between said spindle and 5 said spindle sleeve for simultaneous compression with the spring within said spindle sleeve on the movement of the spindle into the spindle sleeve.

3. In a drilling machine the combination as set forth in claim 1 in which said spindle and 10 said drill are hollow, an ejector tube extending thru said spindle sleeve and said hollow spindle to said drill to guide the chips from said drill thru said hollow spindle and said spindle sleeve.

4. In a drilling machine the combination of an 15 upright, a spindle carrier movable on said upright, an internally threaded spindle sleeve held fixed in said spindle carrier, a spindle movable in and out of said spindle sleeve, a spiral carried by said spindle in threaded engagement with 20 said spindle sleeve, a spring held for compression between said spindle sleeve and said spindle, a drill at the bottom of said spindle, a lever arm for movement of said spindle carrier on said upright to move said drill against the material to 25 be drilled and thus cause the spindle to be forced into said spindle sleeve for the rotation of the spindle by said spiral and the compression of said spring between said spindle and the spindle sleeve to cause the pressure of the spring to force the 30 drill against the material during the rotation of the drill by the spindle.

5. In a drilling machine the combination as set forth in claim 4 including a stop member on said upright for engagement by said spindle to 35 limit the endwise movement of said drill by said spindle in one direction, means for adjusting said stop member relative to said spindle.

6. In a drilling machine the combination of a base, an upright on said base, a spindle carrier 40 movable on said upright, an internally threaded spindle sleeve held fixed in said spindle carrier, a hollow spindle movable in and out of said spindle sleeve, a spiral carried by said spindle in threaded engagement with said spindle sleeve, a 45 spring held for compression between said hollow spindle and said spindle sleeve, a hollow drill at the bottom of said hollow spindle, an ejector tube carried by said hollow drill and extending thru said hollow spindle and spindle sleeve to carry 50 off the chips from said drill, and means for moving said spindle carrier to cause the drill to be moved against the material to be drilled and to cause the hollow spindle to be moved in and out of the spindle sleeve for the rotation of the drill 55 by the hollow spindle while said spindle is held compressed between the hollow spindle and spindle sleeve and exerts pressure on the drill.

7. In a drilling machine the combination as set forth in claim 6 including a chute carried at the top of said spindle sleeve with said ejector tube extending thru said chute and an outlet in said ejector tube leading into said chute for depositing the chips from said ejector tube in said chute.

8. In a drilling machine the combination as set forth in claim 6 including a supporting tray movable on said base in front of said upright, a gauge member carried by said tray, a latch member movable on said upright and means operated by said spindle carrier for operating said latch member to move into and out of engagement with said gauge member.

9. In a drilling machine the combination of a base, an upright on said base, a spindle mov- 75

able on said upright, a drill carried by said spindle, a latch rod movable on said upright parallel to said spindle, a latch carried by said latch rod, means connecting said spindle with said latch rod for movement thereby, a supporting tray movable on said base in front of said spindle, and

means carried by said tray for engagement by said latch rod to lock and unlock said tray on the movement of said spindle.
